CIGARETTE LIGHTERS

Hans Lowenthal, Kensington, London, England, assignor
to Colibri Lighters Limited

Filed Feb. 8, 1962, Ser. No. 171,845

Claims priority, application Great Britain Apr. 14, 1961
3 Claims. (Cl. 67—7.1)

This invention relates to fully automatic igniting mechanisms for cigarette lighters.

Such mechanisms have a spring-loaded fingerpiece, manual movement of which, against the action of its return spring, causes a flint wheel to rotate and produce a spark. On release of the fingerpiece its spring returns the parts of the mechanism to their original positions ready for a further operation.

One kind of fully automatic mechanism comprises a double lever four-bar chain. The fixed link of the four-bar chain is formed by the body of the lighter or a part of the lighter casing and the other link connecting the two levers is formed by the fingerpiece. One of the levers is connected to the flint wheel in such a way that when the lever is rocked by manual movement of the fingerpiece, the wheel is turned and a spark is produced from a flint pressed against the wheel.

According to the present invention, in a lighter having a fully automatic igniting mechanism of the kind described, that lever which is not connected to the flint wheel is two-armed, the fingerpiece being pivoted on one arm and the other arm being acted upon by a spring which is the return spring for the fingerpiece. The two-armed lever may be either straight or be a bell-crank lever. When a bell-crank lever is used, by varying the angle between the two arms of the lever, the spring may be arranged in any suitable position to allow the mechanism to be fitted compactly into the space available in the lighter casing.

The spring may be either a compression or a tension spring, but generally the former is preferred because it can be arranged to fit more compactly into the casing of a lighter, especially a gas-burning cigarette lighter which has a gas reservoir within the lighter casing.

The arrangement in accordance with the invention is particularly advantageous when used with this sort of lighter because both the igniting mechanism and the flint tube which holds the flint for the igniting mechanism may be arranged on one side of the gas reservoir. In the past, the igniting mechanism has usually been located above the gas reservoir and the flint tube has extended downwards from the igniting mechanism through the middle of the gas reservoir and for this purpose the reservoir has had to be formed with a cylindrical recess. This has greatly added to the cost of the production of the reservoir. With both the igniting mechanism and the flint tube beside the reservoir, however, no recess is necessary and the reservoir is both cheaper and may also be stronger than has previously been the case.

An example of a lighter constructed in accordance with the invention and a modification of this example are illustrated in the accompanying drawings, in which:

FIGURE 1 is a sectional front view of the lighter with parts broken away to show details of its internal construction; and

FIGURE 2 is a section as seen in the direction of the arrows on the line II—II in FIGURE 1.

The lighter shown in FIGS. 1 and 2 comprises an outer casing in two sections 1 and 2. The two sections of the casing are detachably fixed together around the centre line of the lighter, as seen from the side; that is in the plane of the section shown in FIGURE 1. Within the casing formed by the two sections 1 and 2 is an inner casing 3 which forms a frame on which the operating mech-

2

anism of the lighter is supported. Within the inner casing 3 is a removable gas reservoir 4 having a refilling inlet 5 and a burner 6.

The automatic igniting mechanism comprises a flint tube 7 containing a flint 8. As is described in detail in our U.S. patent application S.N. 141,182, filed September 27, 1961, the flint is pressed upwards in the tube 7 against the periphery of a flint wheel 9 by an abutment 10 which is part of a wire loop 11 which extends through two diametrically opposite slots 12 in the flint tube 7. The abutment 10 is pulled upwards by the tension of a spiral tension spring 13. The coiled part of the spring 13 is mounted on a core 14.

The flint wheel 9 is rotated by a double lever four-bar chain mechanism which comprises a fingerpiece 15 forming one of the links of the mechanism and a pair of levers 16 and a pair of bell-crank levers 17. The fingerpiece 15 is pivotally mounted on the upper end of the pairs of levers 16, the lower ends of which are pivotally mounted on a pin 18 which also supports the flint wheel 9. The fingerpiece 15 is also pivotally supported on the top of the arms 19 of the pair of bell-crank levers 17, which are themselves pivoted on a pin 17a which also carries the core 14.

One of the levers 16 is connected to the flint wheel 9 by a ratchet, 16a, which causes the flint wheel to rotate and produce a spark from the flint 8 when the lever 16 is rocked from the position shown in dotted lines in FIGURE 1 to that shown at 16' in chain-dotted lines upon depression of the fingerpiece 15. The fingerpiece 15 is normally held in the position shown in full lines in FIGURE 1 of the drawings by a coiled compression spring 20, the bottom of which abuts against a plate 21 which extends between the two sides of the inner casing 3.

The spring 20 is mounted on a rod 22 which prevents it buckling when it is compressed. The upper end of the spring 20 acts on a head 23 on the rod 22 and this head in turn acts upon a pin 24 which extends between the two second arms 25 of the pair of bell-crank levers 17. When the fingerpiece 15 is depressed to rock the levers 16, as already described, it moves from the position shown in full lines in FIGURE 1 to that shown at 15' in chain-dotted lines. This causes the bell-crank levers 17 to rock also. Their arms 19 move to the position shown in chain-dotted lines at 19' and the arms 25 move to the position shown in chain-dotted lines at 25'. The movement of the arms 25 into the position 25' moves the head 23, and with it the rod 22, downwards. The bottom of the rod 22 slides through a hole in the plate 21. This movement of the head 23 increases the compression in the spring 20 and as soon as the fingerpiece 15 is released the spring returns the whole mechanism to its initial position.

Gas must be caused to issue from the burner 6 as the spark is produced by rotation of the wheel 9. This gas supply is brought about by opening a spring-loaded valve within the burner 6. The valve is opened by lifting the head of the burner 6 by rocking a lever 28 which is pivoted at 29. The lever 28 is rocked by depression of its right-hand end 30 by the arm 25 as this moves downward.

It will be seen that the flint tube 7, the spiral tension spring 13 and the spring 20, and its associated parts, fit compactly into the space within the two sections of the outer casing 1 and 2 beside the gas reservoir 4. The gas reservoir therefore has no parts projecting through it and can be made as a plain rectangular tank.

The burner 6 and the filling inlet 5 are arranged side by side and the filling inlet 5 is accessible through an opening in the sections 1 and 2 of the outer casing, which is normally closed by a spring-loaded hinged cover 26. This cover is described in detail and claimed in my co-pending U.S. patent application S.N. 171,846, filed February 8,

The fingerpiece 15 has an integral extension 27 which, when the fingerpiece is in its normal position shown in full lines in FIGURE 1, extends above the burner 6 and keeps dirt out of the casing. When the fingerpiece 15 is depressed the extension 27 is withdrawn laterally into the position shown in chain-dotted lines at 27' and the flame issuing from the burner 6 is accessible within the opening exposed by the movement of the extension 27. This movement is described in detail and claimed in my co-pending U.S. patent application S.N. 171,844, filed February 8, 1962.

Instead of having the spring 20 extending almost vertically downwards away from the fingerpiece 15 its position may be altered to fit in compactly with a different assembly of parts by altering the angle between the two arms of the bell-crank levers 17. The levers 17 need not in fact be bell-cranks, but may have two arms in a straight line and, in this case, the spring 20 would extend more or less horizontally. The arrangement is, however, particularly adaptable to enable it to fit in compactly with various different arrangements of parts in many forms of lighter.

I claim:

1. In a cigarette lighter having a fully automatic igniting mechanism comprising a body having upper and lower ends, an abrasive wheel at the upper end of said body and means for rotating said wheel including a double lever four-bar chain, said four-bar chain including a portion of said body forming a first link, first and second levers, first and second pivot means pivotally mounting said first and second levers respectively on said body portion, a fingerpiece forming a second link pivoted on said first and second levers and means operatively connecting said flint wheel to said first lever for rotation therewith upon operation of said fingerpiece, the improvement comprising first and second arms forming said second lever, and movable with said first lever and fingerpiece between a first position and a second position, said first arm extending in an upward direction from said second pivot means when in said first position and said second arm being

rigidly fixed to said first arm and extending laterally from said pivot means but generally downward when in said second position, said fingerpiece being pivoted on said first arm, an abutment fixed to said body portion below said second arm, a coiled compression spring having one end bearing on said abutment, means pivotally attaching the other end of said spring to second arm, whereby said spring exerts an upward force on said second arm, biasing it toward said first position with increasing effectiveness as said second arm moves from its downward position toward its lateral position in which it is transverse to the direction in which said spring is exerting pressure thereon, and guide means within said spring to prevent buckling thereof upon downward movement of said second arm, said spring being operative to return said four-bar chain to said first position after displacement therefrom to rotate said flint wheel by operation of said fingerpiece.

2. A lighter as claimed in claim 1 in which said guide means is a rod within said spring and said abutment is provided with a hole within which said rod is slidable.

3. A gas-burning cigarette lighter according to claim 1, which has a gas reservoir within a casing, and in which a tube for housing the flint and said spring both extend downwards within the casing on the same side of said gas reservoir.
